UNITED STATES PATENT OFFICE.

HOWARD MORGAN, OF ATLANTIC CITY, NEW JERSEY, ASSIGNOR, BY MESNE ASSIGNMENTS, TO MORGAN AUTO ALARM CORPORATION, A CORPORATION OF NEW YORK.

AUDIBLE ALARM FOR AUTOMOBILES.

1,332,267.

Specification of Letters Patent.

Patented Mar. 2, 1920.

Application filed November 6, 1917. Serial No. 200,538.

To all whom it may concern:

Be it known that I, HOWARD MORGAN, a citizen of the United States, and a resident of Atlantic City, in the county of Atlantic 5 and State of New Jersey, have invented a new and Improved Audible Alarm for Automobiles, of which the following is a full, clear, and exact description.

This invention relates to safety appliances 10 or alarm devices for vehicles and has particular reference to such devices adapted for use on automobiles provided with internal explosion engines.

Among the special objects of the invention 15 is to provide an audible alarm adapted to be set into operation automatically in connection with the exhaust pipe when the engine is started or the machine is operated by any one without authority, so that the fact 20 that the machine is being tampered with will be published immediately and hence the meddler's scheme will be immediately frustrated.

With the foregoing and other objects in 25 view the invention consists in the arrangement and combination of parts hereinafter described and claimed, and while the invention is not restricted to the exact details of construction disclosed or suggested herein, 30 still for the purpose of illustrating a practical embodiment thereof reference is had to the accompanying drawings, in which like reference characters designate the same parts in the several views, and in which—

35 Figure 1 is a plan view of the main portions of my improvement, but with the casing in section on the broken line 1—1 of Fig. 2.

Fig. 2 is a vertical longitudinal section on 40 the line 2—2 of Fig. 1, parts being in elevation.

Fig. 3 is a vertical transverse section on the line 3—3 of Fig. 2; and

Fig. 4 is a plan view of the chassis of a 45 standard type of automobile with my improvement in connection therewith.

10 indicates the engine of an automobile, and 11 indicates the exhaust pipe leading therefrom. At any desired place along the 50 pipe 11 is interposed a casing 12 constituting with its contents my improvement and which will be described now in detail.

The casing may be made of any suitable material and secured in the front end there-

of at 13 is a portion of the exhaust pipe 11 55 communicating with a Y 14. One branch 14^a of the Y lies in alinement with the pipe 11 and has connected to its rear end at 15 a straightaway pipe 16 which projects 60 through the rear end of the casing at 17 and to which is fitted in any suitable manner an extension 11' of the exhaust pipe.

The other branch 14^b of the Y has connected to it in any suitable manner a tubular 65 member 18 which may be rectangular preferably in cross section, and which in the main lies close and parallel to the member 16 and projects through the rear end of the casing at 19 where it may be fitted with a 70 short pipe 20 open to the atmosphere.

In the bottom of the tubular member 18 is formed a rectangular opening 21 and adjacent thereto the opposite lower edge portions are formed with transversely alined 75 bearings 22 for the accommodation of a horizontal shaft 23 for free rotation in said bearings. This shaft 23 carries three members as follows: first, a fan wheel having a hub 24 and a series of blades 25 radiating 80 therefrom. The blades are formed preferably to substantially fill the interior of the tubular member 18, and the special form of said member above stated lends itself immediately to the better coöperation of 85 the blades. See Fig. 3. The axis of the shaft 23 is substantially in the plane of the bottom of the tubular member but just in front of the opening 21, or directly in front of the wheel, is an upwardly and rearwardly 90 projecting bridge member 26 constituting an upward deflection of that portion of the bottom of the member 18 between the wheel and the Y.

On one end of the shaft 23 is fixed a cam 95 wheel 27 having one or more peripheral cams or crests 27^a, and on the other end of the shaft and on the opposite side of the member 18 from the cam wheel is fixed a fly wheel 28. These two wheels are preferably 100 of the same weight and insure an easy reliable rotation of the shaft with the fan wheel.

In the Y 14 is a movable gate 29 shown as mounted upon a vertical axis at 30 located 105 at the crotch of the Y. The gate is adapted to be swung around its axis so as to obstruct either branch of the Y. In Fig. 2 the gate is shown closing the side branch 14^b, as is

also the indication in full lines in Fig. 1, whereas in dotted lines in Fig. 1 the gate is shown across the direct exhaust lines so as to shunt the exhaust gases through the 5 branch 14^b and tubular member 18. Thus the exhaust gases, or the major portion of the same, are caused to act against the blades of the fan wheel 25 causing the same to rotate rapidly. When, however, the gate 10 remains in the normal full line position in Fig. 1 the exhaust gases pass through the straightaway pipe 16 without any effect being made upon the alarm devices.

Any suitable means may be provided to 15 control the position of the gate 29, but for this purpose I prefer a key controlled device including a lock 32 having a bolt 33 from which a link 34 extends to a crank 35 connected to the upper end of the axle 30 of the 20 gate. The position of the bolt lock 33 obviously may be controlled by a key inserted into the slot 36 through the bottom of the vehicle body 37. Hence the position of the bolt 33 determines the position of the gate 25 and the action of the exhaust gases upon the alarm devices.

At any convenient place on or in the casing 12 is located a gong 38 shown herein as secured within the casing at its top. A clapper 39 is pivoted at 40 on a bracket 41 at the rear end of the casing. One end of the clapper co-operates in the usual manner with the gong under the force of a spring 42, while its opposite end is acted upon in succession by the cam crests 27^a against the force of said spring. Hence when the fan wheel is rotated by the blast through the 30 exhaust pipe 11 and member 18 the cam shaped periphery of the cam wheel 27 will 35 cause a violent ringing of the gong. This 40 action will take place as soon as the engine is

started whether the machine has yet been put in motion or not, and so the meddler will not only be surprised at the sound thus produced, but will be deterred from his 45 reptitious program.

In addition to the rotary fan wheel and gong devices I provide also a sort of whistle indicated at 43 and having a tubular connection 44 with one side of the branch 14^b 50 of the Y or the adjacent portion of the tubular member 18 whereby a portion of the exhaust gases may be conveyed through, causing the sounding of the whistle simultaneously with the ringing of the gong.

The device is very simple and cheap of construction and mode of operation and adds but a negligible amount of weight to the machine. Obviously during the normal 60 proper operation of the machine there is no sensible effect produced by the attachment, but when the lock is operated as intended and the machine is left standing the result produced by the unauthorized starting of the engine or running of the car by any one 65 not advised of the safety appliance will be pronounced and immediate.

I claim:

In an audible alarm for automobiles, the combination with an exhaust pipe, an extension leading at an angle from the exhaust pipe and key controlled means to govern the flow of the exhaust gases either directly through the exhaust pipe or through said extension, of a rotary member carried by said 70 extension and caused to rotate rapidly by the exhaust gages when passing through the extension, a cam wheel caused to rotate from said rotary member, a gong, and a pivoted member actuated by said cam wheel and 75 adapted to cause the ringing of the gong.

HOWARD MORGAN.
